UNITED STATES PATENT OFFICE.

EDMUND HOFFMAN, OF BROOKLYN, NEW YORK, ASSIGNOR TO AMERICAN CAN COMPANY, OF NEW YORK, N. Y., A CORPORATION OF NEW JERSEY.

DESIGN FOR A POWDER-CONTAINER.

52,793.

Specification for Design.

Patented Dec. 24, 1918.

Application filed February 19, 1915. Serial No. 9,449. Term of patent 14 years.

To all whom it may concern:

Be it known that I, EDMUND HOFFMAN, a citizen of the United States, residing at Brooklyn, in the county of Kings and State of New York, have invented a new, original, and ornamental Design for a Powder-Container, of which the following is a specification, reference being had to the accompanying drawing, forming a part thereof.

On the drawing:

The figure is a perspective view of a powder container embodying the said design.

The design is characterized by a wide and flat cylindrical body surmounted by a cylindrical cover of less height and diameter, the corner edges of the body and of the cover being beveled on an angle or incline to the vertical walls of the same.

I claim:

The ornamental design for a powder container, as shown.

EDMUND HOFFMAN.
